(57) **CLAIM**

The ornamental design for a miniaturized motor vehicle with storage compartment, as shown and described.

DESCRIPTION

FIG. 1 is a front top perspective view of my miniaturized motor vehicle with storage compartment showing my design; the steering bar assembly and the seat assembly do not form a part of my design and are shown in dashed lines; FIG. 2 is a top plan view of my miniaturized motor vehicle with storage compartment with the seat shown in dashed lines;

FIG. 3 is a right side elevational view thereof with the steering bar assembly and the seat assembly shown in dashed lines, the left side elevational view being a mirror image;

FIG. 4 is a bottom plan view thereof;

FIG. 5 is a front elevational view thereof and with the steering bar assembly and the seat assembly shown in dashed lines; and,

FIG. 6 is a rear elevational view thereof with a part of the seat assembly shown in dashed lines.
